UNITED STATES PATENT OFFICE.

FRANK P. FERRIS, OF LINCOLN, NEBRASKA.

MUSICAL WHISTLE.

Application filed July 5, 1921. Serial No. 482,553.

To all whom it may concern:

Be it known that I, FRANK P. FERRIS, a citizen of the United States, residing at Lincoln, in the county of Lancaster and 5 State of Nebraska, have invented certain new and useful Improvements in Musical Whistles, of which the following is a specification.

My invention relates to a musical whistle 10 of the type of musical horns which are sometimes used on automobiles, trucks, and other vehicles driven by internal combustion motors, and one of its objects is to provide a more perfect control of the tone and of 15 the volume of the musical notes.

Another object of my invention is to produce a non-clogging whistle which will blow out and otherwise eliminate the particles of matter which tend to lodge in the 20 whistle when the exhaust gases from the engine pass through the whistle.

Other objects of my invention will be hereinafter made clearly apparent in the specification and pointed out in the claims.

25 In the accompanying drawings I have shown the preferred form which my invention may take.

In the accompanying drawings, Fig. 1 is a view partly in section and with parts 30 broken away, showing the attachment as applied to the exhaust of a gas engine, and Fig. 2 shows a detail with the knife edge of the piston seated in the slit.

The attachment consists of two parts A 35 and B, A being the whistle proper and B the valve which controls the flow of the exhaust gases through the whistle.

The body of the whistle includes a metallic cylindrical tube 10 screw-threaded on its 40 outer periphery at its upper end at 11 and having its inner and outer walls tapered to a sharp edge at its lower end 12, for purposes hereinafter set forth. On the upper screw-threaded end is secured a cap 13 having a central opening 14 for the passage of a piston rod, and one or more openings 15 serving as an inlet or outlet for the air as the piston is pushed down or up.

At the lower end of the tube 10 is secured 50 a head 16 described in detail as follows: the lower end 17 of the head 16 is cylindrical and is screw-threaded for the attachment to the exhaust either directly or by means of a coupling, as shown in the drawings.

55 The main portion of the head 16 consists of two frusto-conical portions 18 and 19

merged at their bases. The portion 19 comprises a clamping band 20 which is merged with the portion 18 through a plurality of connecting ribs 21 having openings 22 therebetween. The clamping band is slit and is provided on each side of the slit portion with ears 23 which are clamped together by means of screws 24 or any other appropriate fastening means. By attaching this clamping band 20 to the tube 10 near its lower end, the head 16 is firmly secured to the tube 10.

The inner part of portion 18 of the head is cut away with the exception of the lugs 25, preferably four in number, and these are 70 provided with screw threads into which the screw threaded disc 26 fits. The disc 26 is integral with the disc 27, the diameter of which is somewhat greater than that of the disc 26, but slightly smaller than that of the 75 opening into which it fits, thus leaving a narrow circular slit between the disc 27 and the inner surface of the head 16. Gases flowing from the exhaust enter the whistle, pass through between the lugs 25, then 80 through the narrow circular slit above mentioned and into the tube, finally leaving the whistle through the openings 22.

The sound waves are produced by forcing 85 the exhaust gases into the tube 10. For changing the amplitude of the vibrations, a piston 28 is provided to slide in the tube 10. The piston 28 is secured at its central point to a piston rod 29 which slides 90 through the aperture 14 of the cap 13, and at the outer end of the piston rod is secured a hand grip 30.

The piston 28 is provided with a groove 95 into which is inserted a piston ring 31 of the expandable type well known in internal combustion engines. The extremity of the piston is provided with a circular knife edge 32 which fits into the circular slit between the disc 27 and the inner surface of the head. The parts are so proportioned 100 that when the knife edge 32 is seated in the slit, the piston ring is at the tapered end of the tube 10, permitting the ring to expand thus resisting the pressure of the exhaust gases and to a large extent constituting a 105 lock against sudden displacement. While I have shown my invention as applied to a closed pipe it is obvious that it will be equally effective on an open pipe. Only one sound varying in intensity will be produced 110 in an open pipe, but if the cap 13 and the piston 28 are omitted, leaving only a nar-

row cylinder having the circular knife edge 32 and means for thrusting this forward and backward, it would of course serve to keep the passages clear of extraneous matter.

One serious drawback with musical horns formerly in use is their tendency to clog up with solid particles which are carried in the exhaust gases. To obviate this difficulty I 10 have provided an enlarged approach 33 to the slit between the disc 27 and the inner surface of the head. The result of this construction is that the gases are accelerated in their movement through the narrow slit, 15 carrying with them the particles which would otherwise lodge in the slit. The knife edge on the piston also serves to clear the slit, and it has been found that this combination of elements entirely eliminates the 20 troubles which quickly render existing gas-operated whistles useless. The piston 28, ring 31, and knife edge 32 also prevent the accumulation of carbon and gummy deposits on the walls of the pipe, and thus 25 serve the clear tone of the whistle.

The whistle is secured to any portion of the manifold or exhaust pipe by means of the screw threaded portion of the lower end 17 of the head 16, either directly or by 30 means of a coupling 34 of any type desired. To direct the flow of the gases through the whistle at will, a valve is provided at the outer extremity of the exhaust pipe. This valve must be of the flapper type, as a valve 35 of any other type would be blown off by the sudden changes in pressure in the exhaust pipe. The valve consists of a collar 35 which is clamped to the reduced outlet of the exhaust pipe by means of set screws 36, 40 preferably three in number, and integral with the collar are two ears 37. The flapper consists of a circular disc 38 which is large enough to cover the opening in the collar, and this disc 38 has a plurality of lugs 39 45 and 40 extending outwardly radially therefrom. The lug 39 has an ear 41 projecting rearwardly therefrom and this ear 41 fits between the ears 37 and is pivoted thereto. On the upper end of the lug 39 is secured 50 a coiled spring 42, the other end of which is secured to any fixed part of the engine or the body carrying it. The lower ends of the arms 40 have attached thereto cords or wires 43 which are connected preferably to 55 a foot lever within convenient reach of the operator. The valve has a secondary function as a deflector for the exhaust gases. In some of the cars on the market, it has been found necessary to install such deflectors, 60 usually in fixed position, to prevent the exhaust gases from reaching the face of the operator.

Because of the small number and the simplicity of the controls, the invention is 65 particularly applicable to automobiles and

trucks. The volume of the sound is controlled by the foot lever action on the valve, whereby the amount of gas entering the whistle can be easily regulated and quickly varied. The musical notes are made by the 70 movement of the piston 28, and the control of the piston through the hand grip is so sensitive that with a little practice the operator can play the popular airs while driving the car. The sounds thus produced are 75 exceedingly agreeable to the ear, resembling the rich tones of a pipe organ, but if a sudden warning signal is needed, one or two rapid strokes of the piston will result in some of the most startling noises imaginable. Although intended primarily for use 80 on trucks and automobiles, the invention can be applied to any internal combustion engine, movable or stationary, and can be made to serve the same purposes to which 85 steam whistles are put.

What I claim as new is:

1. In a whistle, a pipe, and means for admitting gas under pressure into said pipe, said means comprising an element spaced 90 from the end of the pipe, a narrow slit in the element, said slit being similar to but slightly smaller in outline than the end of the pipe, and an enlarged entrance to said slit.

2. In a whistle, a pipe, means for conducting gas under pressure into the pipe, said means comprising an element spaced from the end of the pipe, a slit in the element, and an entrance to said slit, said entrance having walls which are substantially parallel adjacent the slit but diverging beyond the parallel portion. 100

3. In a whistle, a pipe, means for conducting gas under pressure into the pipe, said means comprising an element spaced from the end of the pipe, a slit in the element, and means slidably in the pipe and adapted to enter said slit for the purpose of dislodging particles of solid matter from the slit. 105

4. In a whistle, a pipe, means for conducting gas under pressure into the pipe, said means comprising an element spaced from the end of the pipe, a slit in said element, a knife edge having the outline of the slit, said knife edge being mounted to slide lengthwise of the pipe and to enter said slit for the purpose of removing particles of solid matter from the slit. 115

5. In a whistle, a cylindrical tube open at 120 one end, a body having a narrow circular slit for the passage of gases, the body being spaced from the open end of the tube, the axis of the cylindrical tube passing through the center of the circular slit, said slit being 125 slightly smaller in diameter than the tube, a piston mounted to slide in the cylindrical tube, said piston having a circular knife edge on the side near the open end of the cylinder, the knife edge having the same cir- 130

5 circumference as that of the aforementioned circular slit, whereby the circular knife edge seats in the circular slit when the piston is thrust home, and means for controlling the movement of the piston.

6. The combination as in claim 5, the cylindrical tube being tapered on its inner surface at its open end, said piston having a circular groove on its periphery, an expandable piston ring seated in said groove, the parts being so proportioned that the distance 10 between the knife edge of the piston and the aforementioned circular slit is substantially equal to the distance between the extensible piston ring and the tapered edge of the cylindrical tube, whereby the piston ring is permitted to expand at the moment when the knife edge of the piston reaches its seat in the circular slit.

15 7. The combination as in claim 5, said circular slit having an approach which is wedge shaped in cross section, whereby the gases will be accelerated in their movement through the circular slit to blow out parti-

cles of matter which tend to lodge in the 25 slit.

8. A valve for controlling the flow of gas from the manifold or exhaust of an internal combustion engine through a whistle, said valve comprising a collar, means for securing the collar to the outlet of the exhaust pipe, a flapper pivoted to the collar, a spring for holding the flapper normally away from the collar, and means for closing the valve 30 at will.

35 9. A whistle comprising a pipe, a collar surrounding and secured to the inlet end of the pipe, the sides of the collar diverging to a position beyond the inlet end of the pipe and then converging, and means on the collar remote from the pipe for securing it to a source of gas in motion, the collar being provided with openings for the exit of the gases, said openings being positioned near the inlet end of the pipe. 40 45

In testimony whereof I affix my signature.

FRANK P. FERRIS.
